America as represented by the Secretary of the
Navy

Application April 18, 1946, Serial No. 662,948

14 Claims. (Cl. 102—70.2)

1

My invention relates generally to detonating devices for explosive charges and more particularly to arming mechanisms for use on torpedoes.

Since a loaded torpedo is a rather dangerous machine safety features to prevent premature firing of the charge of explosive in the warhead are of utmost need. The more complicated such safety devices are the more likely some elements may fail with the result that the charge of explosive may be detonated prematurely or may not be detonated when desired. Further, it is of importance that the arming take place only after the torpedo is a given distance from the launching location.

One broad object of my invention is the provision of a unitary arming mechanism that may be installed either before or after the warhead is charged with the explosive.

Another broad object of my invention is the provision of a unitary arming mechanism that may be installed in the warhead or removed from the warhead without requiring the assembly or disassembly of other elements of a torpedo.

With some of the arming mechanisms in use for electrically fired exploders for torpedoes, the firing charge is brought into arming position by means of a gear train which is actuated by an impeller wheel receiving its propelling force from water flow past the torpedo. At the same time the switch, which closes a set-up circuit to the squibs which fire the exploder, is operated independently by a worm gear arrangement on the torpedo propeller shaft. In effecting these operations, the wires which lead to the squibs in the exploder from the switch are being coiled and pulled up when the exploder arms, making the wires subject to breakage.

It is a specific object of my invention that the arming switch, which closes the set-up circuit in the leads including the squibs be self-contained in the exploder and that it be an integral part of the mechanism which arms the firing charge so that the exploder may be armed electrically and mechanically at the same time through the operation of one group of self-contained mechanisms.

It is also a specific object of my invention to provide a direct grounded short-circuit while the exploder is in the unarmed position, for the squibs so that static charges or leakage currents do not accidentally fire the squibs.

The objects of my invention hereinbefore stated are merely illustrative of still other objects and advantages of my invention, which other objects and advantages will become more apparent from

2

a study of the following specification and the accompanying drawings, in which:

Figure 1 is a sectional view substantially to full scale and on a vertical plane of my arming mechanisms;

Fig. 2 is a sectional view to a smaller scale, on section line II—II of Fig. 1;

Fig. 3 is a sectional view to a smaller scale on section line III—III of Fig. 1;

Fig. 4 is a broken out portion, some parts in section, of the gear train between the impeller wheel and a certain element of the arming mechanism, and

Fig. 5 shows the circuits controlled by my arming mechanism.

In Fig. 1, the base 1 is shown with suitable bolt holes and shoulders so that this base coating with suitable gaskets may be hermetically secured to the sides of a suitable opening in a sub-structure in the warhead of a torpedo (elements not shown). The substructure per se forms no part of this invention. For the purposes of this disclosure, it will suffice to mention that the impeller wheel 2, the bearings for the impeller wheel shaft 3, the gear 4 on the shaft 3 and the worm 4' are all mounted in the sub-structure. The impeller wheel is so mounted that the flow of the water past the torpedo drives the impeller wheel, as shown in Fig. 4, in a counterclockwise direction. Operation of the impeller wheel 2 drives shaft 5 in the direction indicated. Shaft 5 passes through base 1 through suitable liquid seal devices so that sea water is prevented from leaking into the warhead, that is, into the region above the base 1.

Four suitable columns 6, 7, 8 and 9 are at the bottom bolted into the base 1 and at the top similarly secured to the bearing cradle 10. The cradle 10 carries a bearing ring 11 rigidly secured to the cradle. The ring 11 is provided with an annular groove for receiving the ball bearings 12. An annular gear wheel 13, having a mating groove for the ball bearings, is disposed directly above the bearing ring 11.

The annular gear wheel 13 has a depending annular flange 14 provided with a radially projecting portion, or rib 15. The flange 14 fits closely about the bearing ring 11. Any lateral thrusts will thus not dislocate the gear wheel with reference to the fixed cradle. Suitable set screws or other similar means, which do not appear in the section shown, project radially inwardly from the upper annular edge of the cradle so that they project above the rib 15. The gear wheel 13 is thus positively retained in position on the

cradle 10, but is free to rotate with reference to cradle 10.

A generally cylindrically shaped housing 16 having an annular flange 17 at the bottom is bolted to the gear wheel 13 by the bolts 18. The upper end of the housing is provided with a threaded opening 19 receiving the externally threaded plug nut 20. The plug nut 20, when in the position shown in full line in Fig. 1, thus seals off the interior of the chamber formed by the housing 16, gear 13, bearing ring 11, and cradle 10.

The booster charge 21 is disposed in the position shown in the can 22. The can 22 is soldered or brazed to the plug nut 20 and at its downwardly projecting flange is secured by a slip-joint against rotation to the housing 23 for the squibs 24. The can 22 is provided with helically arranged radial projections so disposed that upon rotation of the housing 16 by a given number of revolutions the can will be in the position shown in dotted line in Fig. 1. The housing 23 is provided with a radially projecting tooth 25 which engages the top of the casing 16 at the opening to prevent the casing 23 from moving back down once the can 22 and casing 23 are in the top position.

From the foregoing description it will be apparent that the squibs and the booster charge 21 are sealed off from the explosive in the region above and about casing 16. Accidental firing of the booster charge 21 before the mechanical arming is complete will merely build up a temporary pressure within the chamber formed by the housing 16, gear wheel 13, bearing ring 11 and cradle 10. By the time the hot gases have leaked out of the chamber through such channels as 26 and 27, their effectiveness to explode the main charge of explosive have largely been dissipated.

Since mechanical isolation of the booster charge before the mechanical arming is complete may not suffice, I also provide safety features to prevent electrical arming of the squibs 24 before the mechanical arming has taken place. The squibs 24 are in a circuit 28 grounded and short circuited by contacts 29 and 30 contacting the base 1 to thus remove the short-circuit from the squibs and putting the squibs on open circuit.

The housing 23, and thus the squibs 24, are mounted on the piston assembly 31 having the piston rod 32. At the bottom of the piston rod 32 I secure a block of insulation 33 carrying the resilient contacts 29 and 30 secured respectively to the terminals of the squibs. The block of insulation 33 also carries the resilient contacts 29' and 30' similarly connected to the terminals of the squibs 24. As long as the piston rod 32 is all the way down the contacts 29 and 30 short-circuit and ground the squibs 24 but as soon as the rod 32 moves up a selected distance, the squibs are on open circuit.

The firing circuit includes a battery B, lead 34, contact 35, inertia member 36, lead 37, contact 38, contact 30', the circuit 28 including the squibs 24, contact 39, contact 29' and lead 40 to the battery. To provide a compact structure—one that may be readily mounted in the warhead and removed therefrom—I secure the leads 37 and 40 to contacts 33 and 39, respectively, as shown. These leads 37 and 40 are carried into the bottom of the electric plug 41 mounted in a suitable

bracket 42 bolted to the warhead. The electric plug 41 comprises male and female sections so that leads 37 and 40 may be readily plugged into the firing circuit or removed therefrom all from the side occupied by base 1. The whole arming structure may thus be readily removed from the torpedo.

The contacts 33 and 39 are secured to the cradle 10 by suitable blocks of insulation 43 and 44. The block of insulation 33 is provided with the projections 45 and 46 engaging columns 7 and 8 respectively. The vertical movement of contacts 29' and 30' is thus guided so that when the contacts are all the way up, they will engage, respectively, the contacts 39 and 38.

Before the torpedo is launched, all the elements are in the position shown in full line in Fig. 1. After launching of the torpedo, the propulsion equipment starts and the torpedo then proceeds through the water toward the target. The flow of the water past the torpedo actuates the impeller wheel 2. This impeller wheel drives the shaft 5 through the gear train already explained. Shaft 5 operates gears 47, 48, 49, 50 and 13 in the directions indicated. Rotation of gear 13 drives the housing 16 and as a consequence the plug nut 20 begins to move up carrying the contacts 29 and 30 and 29' and 30' upwardly.

After the torpedo has moved a selected relatively short distance from the launching position, the contacts 29 and 30 move away from the base 1 to thus remove the short-circuit from the squibs and putting the squibs on open circuit.

After the torpedo has moved a relatively large distance from the launching position, the contacts 29' and 30' engage contacts 39 and 33 respectively. A moment later, since contacts 29' and 30' are resilient, the charge 21 is in the top position and lug 25 maintains the mechanical arming, whereas the contacts 29' and 30' maintain the electrical arming. As soon thereafter as the torpedo strikes its target, the inertia switch or member 36 moves in contact with the contact member 35. The squibs are thus connected to the battery. The squibs explode the charge 21 which rips the can from its slip joint. The effect of the explosion of charge 21 is thus carried to the main charge of explosive and in consequence the main charge of explosive is detonated.

While I have described but one preferred embodiment of my invention, I do not wish to be limited to the exact showing made but wish to be limited only by the scope of the claims hereto appended.

I claim as my invention:

1. In an arming device for a torpedo, in combination, a base fixed to the torpedo, an inverted cup-shaped member disposed in rotatable relation to the base and forming with the base a substantially sealed off chamber, a plug-nut secured in the top of the member having threaded engagement with the member, said plug nut being fixed against rotation with reference to the base but having free translatory motion whereby rotation of said member in a given direction will cause said plug-nut to move out of the member to provide an opening from the chamber to the region outside of the chamber, means for rotating the member in the said given direction, a detonator so mounted on the plug-nut to be in the chamber when the plug-nut is in threaded engagement with the member, and means for electrically arming the detonator at substantially the same time the chamber is opened to the

outside by the unscrewing of the plug-nut from the member.

2. In an arming device for a torpedo, in combination, a sub-base secured in an opening in the side wall of the warhead of a torpedo, said sub-base sealing the torpedo warhead against leakage of water into the warhead, an impeller rotatably mounted in the sub-base, rotary motion transmitting means extending through the sub-base from the impeller to the inside of the warhead, a base in the warhead fixed in spaced relation to the sub-base, a member rotatably mounted on the base, said rotary member being so shaped that together with the base a closed chamber is formed, a detonator of the electrical-ly actuated type in the closed chamber, a traveling nut forming a closure for the chamber, means for restraining said traveling nut against rotation, transmission means between the rotary transmission means and the member for rotating the member to cause said traveling nut to move out of the member to open it to the explosive in the torpedo to thus effect mechanical arming of the torpedo, means operable by the traveling nut also electrically arm the detonator.

3. In an arming device for a torpedo, in combination, a housing consisting of two elements one fixed to the torpedo and the other element fixed on the first element to have rotary motion with reference thereto, a detonator of the electric type disposed in the housing, a traveling nut threaded in the rotary element, means secured to the element of said housing fixed to the torpedo operatively engaging said traveling nut to restrain the said nut against rotation, means for rotating the rotary element as a function of the distance the torpedo travels from its launching position to cause said traveling nut to move out of the rotary element to open the housing to the explosive charge in the torpedo to thus effect mechanical arming of the torpedo.

4. In an arming device for a torpedo, in combination, a housing consisting of two elements one fixed to the torpedo and the other element fixed on the first element to have rotary motion with reference thereto, a detonator of the electric type disposed in the housing, a traveling nut threaded in the rotary element, means secured to the element of said housing fixed to the torpedo operatively engaging said traveling nut to restrain the said nut against rotation, means for rotating the rotary element as a function of the distance the torpedo travels from its launching position to cause said traveling nut to move out of the rotary element to open the housing to the explosive charge in the torpedo to thus effect mechanical arming of the torpedo, and switching means operable by the traveling nut to cause electrical arming of the detonator.

5. In an arming device for a torpedo, in combination, a housing consisting of two elements one fixed to the torpedo and the other element fixed on the first element to have rotary motion with reference thereto, a detonator of the electric type disposed in the housing, a traveling nut threaded in the rotary element, means, secured to the element of said housing fixed to the torpedo, operatively engaging said traveling nut to restrain the said nut against rotation, means for rotating the rotary element as a function of the distance the torpedo travels from its launching position to cause said traveling nut to move out of the rotary element to open the housing to the explosive charge in the torpedo to thus effect mechanical arming of the torpedo,

and switching means operable by the traveling nut to cause electrical arming of the detonator, said switching means being so coupled to the traveling nut that the electrical arming takes place substantially at the same time the mechanical arming is effected.

6. In an arming device for a torpedo, in combination, a housing consisting of two elements one fixed to the torpedo and the other element 10 fixed on the first element to have rotary motion with reference thereto, a detonator of the electric type disposed in the housing, a traveling nut threaded in the rotary element, means, secured to the element of said housing fixed to the torpedo, operatively engaging said traveling nut to restrain the said nut against rotation, means for rotating the rotary element as a function of the distance the torpedo travels from its launching position to cause said traveling nut to move out of the rotary element to open the housing to the explosive charge in the torpedo to thus effect 20 mechanical arming of the torpedo, and switching means operable by the traveling nut to cause electrical arming of the detonator, and 25 means for short-circuiting the detonator as long as the traveling nut is in its position in the second element to prevent electric energization of the detonator because of either leakage currents or static charges, or both.

7. In an arming device for a torpedo, in combination, a housing consisting of two elements one fixed to the torpedo and the other element fixed on the first element to have rotary motion with reference thereto, a detonator of the electric 35 type disposed in the housing, a traveling nut threaded in the rotary element, means, fixed with reference to the torpedo, engaging said traveling nut to restrain it against rotation, means for rotating the rotary element as a function of the 40 distance the torpedo travels from its launching position to cause said traveling nut to move out of the rotary element to open the housing to the explosive charge in the torpedo to thus effect mechanical arming of the torpedo, switching 45 means operable by the traveling nut to cause electrical arming of the detonator, said switching means being so coupled to the traveling nut that the electrical arming takes place substantially at the same time the mechanical arming is effected, and means for short-circuiting the detonator as long as the traveling nut is in its position in the second element to prevent electric energization of the detonator because of either leakage currents or static charges, or both.

8. In an arming device for a torpedo, in combination, a housing consisting of two elements one fixed to the torpedo and the other element disposed on the first element to have rotary motion only with reference thereto, a detonator including a booster charge and a firing squib, said firing squib having a circuit provided at each end with a contact element, a traveling nut threaded into the rotary element, means for restraining rotation of said traveling nut when said rotary element is rotated, means for rotating the rotary element as a function of the distance of travel of the torpedo from its launching position to cause said traveling nut to move out of the rotary element to open the housing to the explosive charge in the warhead to thus effect mechanical arming of the torpedo, said contact elements being connected to said traveling nut to cause electric arming of the firing squib.

9. In an arming device for a torpedo, in combination, a housing consisting of two elements

one fixed to the torpedo and the other element fixed on the first element to have rotary motion with reference thereto, a detonator including a booster charge and a firing squib, said firing squib having a circuit provided at each end with a contact element, a traveling nut threaded into the rotary element, said traveling nut carrying said detonator, means for restraining rotation of said traveling nut when said rotary element is rotated, means for rotating the rotary element as a function of the distance of travel of the torpedo from its launching position to cause said traveling nut to move out of the rotary element to open the housing to the explosive charge in the warhead to thus effect mechanical arming of the torpedo, and electric supply terminals for the contact elements fixedly mounted on the element of the housing fixed to the torpedo, said contact elements being connected to said traveling nut to thus move into engagement with the electric supply terminals upon rotation of said rotary element to cause electric arming of the firing squib.

10. In an arming device for a torpedo, in combination, a housing consisting of two elements one fixed to the torpedo and the other element fixed on the first element to have rotary motion with reference thereto, electric supply terminals on the element fixed to the torpedo, a detonator including a booster charge and a firing squib, said firing squib having a circuit provided at each end with a contact element, a traveling nut threaded into the rotary element, means rigidly coupled to the torpedo and operatively engaging said traveling nut to restrain it against rotation upon rotation of the rotary element, means for rotating the rotary element as a function of the distance of travel of the torpedo from its launching position to cause said traveling nut to move out of the rotary element to open the housing to the explosive charge in the warhead to thus effect mechanical arming of the torpedo, said contact elements being connected to said traveling nut to cause electric arming of the firing squib, said contact elements being so coupled to the traveling nut with reference to the supply terminals that electrical arming takes place at substantially the same time as the mechanical arming is effected and means for short-circuiting the contact elements as long as the traveling nut is in said rotary element.

11. In an arming device for a torpedo, in combination, a housing consisting of two elements one fixed to the torpedo and the other element fixed on the first element to have rotary motion with reference thereto, a detonator including a booster charge and a firing squib, said firing squib having a circuit provided at each end with a contact element, a traveling nut threaded into the rotary element, means rigidly coupled to the torpedo and operatively engaging said traveling nut to restrain it against rotation upon rotation of the rotary element, means for rotating the rotary element as a function of the distance of travel of the torpedo from its launching position to cause said traveling nut to move out of the rotary element to open the housing to the explosive charge in the warhead to thus effect mechanical arming of the torpedo, electric supply terminals for the contact elements mounted on the element fixed to the torpedo and disposed in the path of the contact elements, said contact elements being connected to said traveling nut to move into engagement with the supply terminals to cause electric arming of the firing squib, and means for short-circuiting the contact ele-

ments as long as the traveling nut is in threaded engagement with the rotary element.

12. In an arming device for a torpedo, in combination, a housing consisting of two elements one fixed to the torpedo and the other element mounted on the first element to have rotary motion with reference thereto, a detonator including a booster charge and a firing squib, said firing squib having a circuit provided at each end with a contact element, a traveling nut threaded into the rotary element, means mounted to be fixed with reference to the fixed element and operatively engaging the traveling nut to restrain rotation of said nut upon rotation of the rotary element, means for rotating the rotary element as a function of the distance of travel of the torpedo from its launching position to cause said traveling nut to move out of the rotary element to open the housing to the explosive charge in the warhead to thus effect mechanical arming of the torpedo, said contact elements being connected to said traveling nut to cause electric arming of the firing squib, electric supply terminals for the contact elements mounted on the element fixed to the torpedo and disposed in the path of the contact elements, said contact elements being so coupled to the traveling nut with reference to the supply terminals that electrical arming takes place at substantially the same time as the mechanical arming is effected and means for short-circuiting the contact elements as long as the traveling nut is in said rotary element.

13. In an arming device for the explosive charge in the warhead of a torpedo in combination, a sub-base fixed in an opening in the torpedo warhead to seal the opening, a base fixed in spaced relation on the sub-base by guide means extending from the sub-base to the base, a rod slidably disposed through the base so as to have one end disposed in the space between the sub-base and base and the other end disposed above the base, means on said rod engaging said guide means to effect only translating motion of said rod, a firing squib, a booster charge, and nut fixed on the end of the rod disposed above the base, electrical supply terminals disposed on the base on the surface facing the sub-base, said firing squib having a circuit comprising a pair of leads extending from the terminals of the firing squib longitudinally of the rod to the end of the rod disposed in the space between the base and the sub-base, contacts on the ends of the leads so disposed as to engage the supply terminals upon longitudinal movement of the rod to its upper position, a housing generally of the shape of an inverted cup rotatably mounted on the base, said nut being normally mounted in a threaded opening in the housing, whereby said nut, housing and base form a closed chamber for housing the firing squib and booster charge, an impeller wheel rotatably mounted in the sub-base in the path of the water flow past the torpedo as the torpedo moves through the water, transmission means between the impeller wheel and the housing to effect rotation of the housing, whereby the nut is caused to move out of the housing and the booster charge is moved out of the housing and the contacts on the lower end of the rod make contact with the supply terminals to thus effect mechanical and electrical arming and mechanical arming of the warhead.

14. In an arming device for the explosive charge in the warhead of a torpedo in combination, a sub-base of electrical conducting material

fixed in an opening in the torpedo warhead to seal the opening, a base fixed in spaced relation on the sub-base by a guide means extending from the sub-base to the base, a rod slidably disposed through the base so as to have one end disposed in the space between the sub-base and base and the other end disposed above the base, means on said rod engaging said guide means to guide said rod for longitudinal movement only, a firing squib, a booster charge, and nut fixed on the end of the rod disposed above the base, electrical supply terminals disposed on the base on the surface facing the sub-base, said firing squib having a circuit comprising a pair of leads extending from the terminals of the firing squib longitudinally of the rod to the end of the rod disposed in the space between the base and the sub-base, contacts on the ends of the leads so disposed as to engage the supply terminals upon longitudinal movement of the rod to its upper position, said rod normally being in its lowermost position so that the contacts at the lower end of the rod engage the sub-base to short-circuit and ground the firing squib to prevent firing of the squib by either leakage currents or static charges, or both, a housing generally of the shape of an inverted cup rotatably mounted on the base, said nut being normally mounted in a threaded open-

ing in the housing, whereby said nut, housing and base form a closed chamber for housing the firing squib and booster charge, an impeller wheel rotatably mounted in the sub-base in the path of the water flow past the torpedo as the torpedo moves through the water, transmission means between the impeller wheel and the housing to effect rotation of the housing, whereby the short-circuit for the firing squib is removed and the nut is caused to move out of the housing and the booster charge is moved out of the housing and the contacts on the lower end of the rod make contact with the supply terminals to thus effect mechanical and electrical arming and mechanical arming of the warhead.
